Application May 11, 1948, Serial No. 146,287

Term of patent 14 years

(Cl. D72—1)

To all whom it may concern:

Be it known that we, Robert F. Broussard and Charles A. Toce, both citizens of the United States and residents of Houston, in the county of Harris and State of Texas, have invented a new, original, and ornamental Design for a Traffic Signal, of which the following is a specification, reference being had to the accompanying drawing, forming part thereof, wherein:

Figure 1 is a top plan view of a traffic signal showing our new design;

Fig. 2 is a side elevation thereof;

Fig. 3 is a front perspective view thereof; and

Fig. 4 is a rear perspective view thereof.

The dotted lines shown in the drawing are for illustrative purposes only.

We claim:

The ornamental design for a traffic signal, as shown and described.

ROBERT F. BROUSSARD.
